UNITED STATES PATENT OFFICE.

ALLEN G. SINCLAIR, OF BROOKLYN, NEW YORK.

CANISTER-SHOT.

SPECIFICATION forming part of Letters Patent No. 292,065, dated January 15, 1884.

Application filed December 1, 1879.

To all whom it may concern:

Be it known that I, ALLEN G. SINCLAIR, of the city of Brooklyn, in the county of Kings, State of New York, have invented certain new and useful Improvements in Canister-Shot; and I do hereby declare that the following specification, when taken in connection with the accompanying drawings, is such a full, clear, and exact description as will enable others skilled in the art to make and use the same.

My invention relates to the construction of canister-shot for ordnance; and it consists in the use, in the construction with the usual small balls employed in this class of ammunition, of a holder for the reception of the balls, constructed of a spirally-wrapped wrought-iron or other metallic wire, (differing in diameter according to caliber,) the whole being 15 cased in an ordinary outside cylindrical tin case, said parts being assembled by mechanical means and secured by bottom and top metallic caps, held in place by bending over and properly compressing the ends of the outside in- 20 closing-case, so as to form retaining-flanges.

The action of canister-shot when discharged is as follows: When ordinary canister is fired, the tendency of the bullets is to rapidly separate, and as the restraining elements in ordinary canister are not sufficient to control this tendency to separate, a wide dispersion near the muzzle of the gun follows, and in consequence a loss of useful effect at ranges, say, up to three hundred yards results. The 30 spiral wire holder operates to retard the lateral dispersion of the bullets, for the reason that it gradually elongates under the tendency of the bullets to diverge rapidly from the line of fire, and thus has its spirals gradually spread 35 apart sufficiently to admit the passage of the balls held within it, and thereby causing the gradual dispersion of the balls, and hence secures at ordinary canister-ranges the maximum effect of this class of projectile, say up 40 to three hundred yards. Other devices to obtain the same end are in vogue; but this one secures all the advantages of restraint in a greater degree, and is more economical in its 45 construction.

Figure 1 is a sectional elevation of the empty case. Fig. 2 shows the case in section and

elevation as filled with bullets. Fig. 3, in a similar manner, shows another construction.

The base 2 and head 4 are each constructed of wrought-iron or other suitable metal, of such shape as is best adapted to support the balls 1 and be secured in place by the case 3. The case 3 is composed of sheet-tin or similar plate metal lap-joined or otherwise secured in circular form. The holder 5 is formed of 55 wire, preferably soft wrought-iron wire, which is coiled into spiral form by any common means and of a diameter to suit the case 3 and its base 2 and head 4. It is preferable that the spiral coils of the holder shall be so wrapped 60 as to bring their surfaces in immediate contact; but a slight space may be left between them. The case 3 may be omitted when some wire of proper gage is used for the holder; but that omission necessitates the adoption of ex- 65 pensive means for connecting the head 4 and base 2 to said holder. 70

The mode of assembling is as follows: The case 3 is first made in the ordinary manner and of the desired dimensions. The spirally-wound wire holder, of proper diameter, is then inserted within the case 3, so as to rest upon the base 2, which is placed within the case 3, so that the flanged lower end, 6, of the case is lapped over the said base 2. The balls are 80 next inserted in the case, and the head 4 is placed within the case and its upper edges are turned over the edge of the head 4, as in Figs. 1, 2, or pressed against the tapering side walls of the same, as in Fig. 3. The whole is then 85 compressed together by pressure, so as to completely assemble the ammunition and finish the projectile for service.

Any form of head 4 may be adopted, and the flange 6 may be formed in the case 3, either before or while assembling the parts; and any other mode of construction may be employed. 90

I am aware that there exists a double or multiple spiral of wires united together at one end and free at the other end, the coils of said 95 spirals being widely separated, whereby said independent spirals will, during the flight of the projectile, spread apart laterally at the unattached ends and liberate the shrapnel or filling. 100

I therefore claim—

1. A holder for the bullets of canister-shot,

consisting of a single wire wound in a spiral, with its coils laid closely together, whereby the small balls are normally confined in place, and are gradually dispersed during the flight 5 of the projectile by the gradual spreading of said spirals.

2. The combination of a spirally-wound wire holder, a suitable head and base, and connecting means constituting the envelope for canister-shot, substantially as described.

3. The combination of a spirally-wound wire holder, a sheet-metal case, a metal base, and metal head, all substantially as described.

In testimony whereof I have signed my name to this specification in the presence of two sub- 15 scribing witnesses.

ALLEN G. SINCLAIR.
